UNITED STATES PATENT OFFICE.

JAMES S. HARRIS AND JAMES A. GRAHAM, OF THOMPSONVILLE, ILLINOIS, ASSIGNEES
OF ONE-THIRD TO THOMAS G. PUCKETT AND ONE-THIRD TO DAVID D. PUCKETT,
BOTH OF THOMPSONVILLE, ILLINOIS, AND ONE-THIRD TO SAID GRAHAM.

SUBSOILER.

1,109,063.

Specification of Letters Patent.

Patented Sept. 1, 1914.

Application filed March 11, 1914. Serial No. 824,012.

To all whom it may concern:

Be it known that we, JAMES S. HARRIS and JAMES A. GRAHAM, citizens of the United States, residing at Thompsonville, 5 in the county of Franklin and State of Illinois, have invented certain new and useful Improvements in Subsoilers, of which the following is a specification, reference being had to the accompanying drawings.

10 This invention relates to certain improvements in subsoilers and the object of the invention is to provide a device of this general character having novel and improved means whereby the same may be operatively connected with the beam of a plow proper with convenience and facility and in such a manner whereby the depth of penetration of the subsoiler may be readily regulated, as the necessities of practice may require.

20 The invention consists in the details of construction and in the combination and arrangement of the several parts of our improved subsoiler whereby certain important advantages are attained and the device is 25 rendered simpler, less expensive and otherwise more convenient and advantageous for use, all as will be hereinafter more fully set forth.

The novel features of the invention will 30 be carefully defined in the appended claim.

In order that our invention may be the better understood, we will now proceed to describe the same with reference to the accompanying drawings, wherein—

35 Figure 1 is a view in side elevation of a plow showing a subsoiler constructed in accordance with an embodiment of our invention in applied position thereon; Fig. 2 is a sectional view taken substantially on the 40 line 2—2 of Fig. 1; and Fig. 3 is a sectional view taken substantially on the line 3—3 of Fig. 1.

45 As disclosed in the accompanying drawings, 1 denotes a plow beam as generally employed in connection with a walking or sulky plow and, as herein disclosed, is substantially I-shaped in cross section and has its rear extremity bent or curved downwardly, as at 2, and to which depending 50 portion is adapted to be secured, in the usual way, the conventional plow 3.

At a predetermined point along the substantially horizontal portion of the beam 1 and to one side thereof is positioned the

block member 4 having the recess or pocket 55 5, such block being clamped to the beam 1 through the medium of the clamping bolts 6 passing above and below the beam 1 whereby it will be readily perceived that such beam is in no wise weakened as would be 60 the case if such bolts were directed through suitable openings in the beam, as is generally done. The clamping bolts or members 6 also serve to hold in operative position against the opposite side of the beam 1, 65 the depending member 7 formed on the forward extremity of the elongated member 8 which serves as a brace for the rack member 9, the length of the member 8 being such as to permit the lower angular portion 10 70 of the rack to be clamped to the beam 1 at the bend thereof, such portion 10 being provided with suitable openings through which conventional hook bolts are projected in order to create the requisite clamping action, 75 in a manner which is believed to be obvious.

Within the pocket or recess is suitably pivoted, as indicated at 11, the forward extremity of the subsoiler beam 12 which may be of any ordinary or preferred construction and terminating in a proper position relative to the plow 3. To either side of the rack 9 the beam 12 is provided with the upstanding straps 14, to the upper extremities of which are suitably secured the bar 15, 80 the rear portion of such bar 15 being extended, as indicated at 16, in order to afford a convenient hand grasp. Slidably mounted upon the bar 15 is the spring actuated pawl 17 normally in engagement with the rack 9 85 90 but adapted to be disengaged therefrom through the medium of the lever 18 pivotally connected with the bar 15 and overlying the projected or handle portion 16, such lever being operatively connected with the 95 pawl 17 through the medium of the link member 19.

When it is desired to regulate or adjust the extent of penetration of the plow member 20 carried upon the lower extremity of the subsoiler beam 12, it is only necessary that such beam be swung upon its pivotal connection, with the block 4, through the medium of the bar 15, in a manner which is believed to be self-evident. 100 105

In order that the beam 12 will be effectively maintained against undue lateral movement, we find it of advantage to have

the rack 9 comprised of two spaced members 21 affording therebetween an elongated opening 22 through which such beam 12 is directed.

5 From the foregoing description, it is thought to be obvious that a subsoiler constructed in accordance with our invention is of an extremely simple and comparatively inexpensive nature and is particularly well 10 adapted for use by reason of the convenience and facility with which it may be assembled and by reason of the effectiveness with which it performs its several functions, and it will also be obvious that our invention 15 is susceptible of some change and modification without material departure from the principles and spirit thereof and for this reason we do not wish to be understood as limiting ourselves to the precise arrangement and formation of the several parts herein shown in carrying out our invention in practice.

Having thus fully described our invention what we desire to claim and secure by Letters Patent, is:

20 In combination with a plow beam, a block positioned to one side of the beam and provided with an opening disposed substantially parallel to the beam, an elongated member positioned above the beam and provided at one extremity with a depending member overlying the beam at the side thereof opposite to the block, clamping means

common to the block and the depending member for holding the same to the beam, a 35 rack depending from the opposite extremity of the elongated member and overlying the beam, means for clamping the overlying portion of the rack and the beam, a subsoiler beam having one extremity projecting within the opening of the block and pivotally engaged therewith and of a length to project rearwardly of the rack, a bar positioned above and carried by the subsoiler beam and provided with an extension to afford a hand grasp, a latch mechanism carried by the bar and engaging with the rack whereby the subsoiler beam may be maintained in differing adjustments about its pivoted connection with the block, said latch 45 including a member overlying the projected portion of the bar whereby the latch may be operated by the hand in engagement with the projected portion, the clamping means for the block and depending member and the clamping means for the rack constituting the only point of engagement with the plow beam.

50 In testimony whereof we hereunto affix our signatures in the presence of two witnesses.

JAMES S. HARRIS.

JAMES A. GRAHAM.
